[57] **CLAIM**

The ornamental design for a lavatory, as shown and described.

DESCRIPTION

FIG. 1 is a left, top, front perspective view of a lavatory embodying my new design;

FIG. 2 is a top plan view thereof;

FIG. 3 is a front elevational view thereof;

FIG. 4 is a right side elevational view thereof, the left side elevational view being a mirror image of the right side shown;

FIG. 5 is a cross-sectional view taken along line 5—5 of FIG. 2; and,

FIG. 6 is a cross-sectional view taken along line 6—6 of FIG. 2; and,

The broken line representations of holes in FIGS. 1 and 2 are for purposes of illustration only, and form no part of the claimed design.
